ELEVATOR CONTROL AND SIGNALING
SYSTEMFrank E. Lewis, East Pittsburgh, Pa., assignor to
Westinghouse Electric & Manufacturing Com-
pany, a corporation of PennsylvaniaApplication August 26, 1929, Serial No. 388,310
Renewed August 15, 1934

18 Claims. (Cl. 187—29)

My invention relates to systems of control and has particular relation to control systems applied to elevators, hoists and similar machinery.

In modern elevator installations, it is usual to have a number of elevators operating in adjacent hatchways past the same floors to thereby constitute a bank or battery of elevators giving service to all of the floors past which the cars move. The most efficient service in such battery or bank of elevator installations is achieved when the elevators are so spaced apart in the hatchways that each of the elevators in the bank passes a given floor at substantially regularly spaced time intervals.

However, due to the variable nature of the traffic conditions under which elevators are operated, it frequently happens that an elevator makes a greater number of stops during one trip than does the next following elevator, and in this manner, the following elevator will overtake the first and thereafter run substantially in unison with the first car.

It is readily apparent that such condition means that at any floor at which a passenger desires to board the car, both elevators will arrive at approximately the same time, both will stop and the passenger will have to choose between the one or the other of the cars.

Such operation is inefficient, since one of the cars will have made the stop for no purpose, and it is to avoid such operation as this that I have devised a system which will prevent two cars from stopping at the same floor and which will ensure that the cars shall be spaced apart in the hatchway.

An object of my invention, therefore, is to provide a control system for a bank of elevators wherein the cars will be forced to become spaced apart in the hatchways.

Another object of my invention is to provide a control system for a bank of elevator cars wherein any car provides a block extending any selected number of floors in advance of the car to prevent any following or overtaking car from receiving calls to stop within the block defined by the first car.

Another object of my invention is to provide a call system for a bank of elevator cars wherein the calls for service are receivable by but one car in the bank at any one time, independently of the simultaneous approach of several cars.

Another object of my invention is to provide a call system for a bank of elevator cars, as outlined in the preceding paragraph, in which the first car to approach within a predetermined distance of a

floor at which a call is registered shall receive the call and prevent the call from being received by any other car in the bank.

Another object of my invention is to provide a control system for a bank of elevator cars wherein a call for service may be registered for all of the elevator cars in the bank but which is receivable only by the first car to approach the corresponding floor, to the exclusion of all other cars, and in which, until the first car to approach the floor has left the floor after making the required stop, shall prevent the stopping of any other car at that floor in response to calls for service registered prior to the actual departure of the said first car.

Another object of my invention is to provide a control system for a bank of elevator cars in which floor lanterns provided at the floors for indicating the approach of a car shall be illuminated in advance of the approach of the car when the car is at any predetermined distance in advance of the corresponding floor.

Another object of my invention is to provide a call system for a bank of elevators whereby registered calls for service at the several floors are maintained until the call has been answered by the stopping of a car at the corresponding floor in response thereto.

Other objects of my invention will be developed in the description of my invention when read in conjunction with the accompanying drawings, wherein

Figures 1 and 2 jointly constitute a diagrammatic view of an elevator installation embodying my invention as applied to a bank of two elevator cars.

Referring to the drawings, I have illustrated two elevator cars C and C' operating in adjacent hatchways (not shown) to serve six floors indicated by the broken lines marked 2nd, 3rd, 4th, etc.

Each of the elevator cars C may be suitably driven by means of a variable-voltage drive, that for car C constituting an elevator-hoisting motor EM having its armature directly coupled to a hoisting drum D over which passes a cable CA attached, at one end, to the elevator car C and, at the other end, to a suitable counterweight (not shown).

The elevator motor EM is provided with a separately-excited field winding EMF connected, for constant-voltage energization, to a source of current indicated by line conductors L1 and L2. The armature of the elevator motor EM is connected in loop circuit with the armature of a generator 50 55

G which, in turn, is provided with a separately-excited field winding GF and a cumulative series field winding GSF. The armature of the generator G is suitably driven at a constant speed by means of a driving motor M, illustrated as of the shunt-wound type having its armature and its field winding MF connected in parallel relation to the source of current L₁ and L₂.

The direction and speed of operation of the elevator car C may be suitably controlled by varying the direction and amount of excitation current supplied to the generator and separately-excited field winding GF by manipulation, respectively, of an up-direction switch 1, a down-direction switch 2 and a speed relay 3 which, in turn, are controlled by a car switch Cs mounted upon the car C to be actuated by an attendant on the car.

While my system is adapted for use with any of the elevator control systems which will provide for stopping the car accurately level with the floors which it serves, I have illustrated my system as applied to an automatic inductor-landing system of the type shown in the copending application of E. M. Bouton, Serial No. 731,291, filed August 14, 1924 and assigned to the Westinghouse Electric & Manufacturing Company wherein the direction switches 1 and 2 and the speed switch 3, when actuated, are maintained in operative position until the car passes predetermined points in the hatchway in advance of the floors at which stops are to be made, at which times, inductor relays will automatically cause deenergization of these switches and relays at the appropriate times to cause the car to be brought to a stop at the floor level.

I have illustrated a plurality of inductor relays carried by the car C, including a stop relay SR for stopping the car at the floor level, an up slow-down inductor relay UR for initiating deceleration in advance of stopping when the car is travelling upwardly and a down slow-down inductor relay DR for initiating deceleration when the car is travelling downwardly.

In order that a car which is to stop at any floor may indicate this fact in advance of the arrival of the car at the floor, each of the cars is provided with a group of hall lanterns associated with the floors which it serves; those for car C being designated by the reference characters 1L at the first floor, 2LU and 2LD at the second floor to indicate, respectively, the approach of the car C, when travelling in the upward and downward directions. In like manner, hall lanterns 3LU, 3LD, 4LU, 4LD, 5LU, 5LD and 6L perform similar services for the third, fourth, fifth and sixth floors, respectively.

To enable passengers on a car to signify their desires to leave the car at the several floors, a plurality of push buttons are mounted upon the car to be operated either by the passengers thereon or by the attendant in response to notification by the passengers to thereby register the stops which are to be made for the exit of passengers from the car. These buttons are designated by the reference characters C₂, C₃, C₄ and C₅ for the second, third, fourth and fifth floors, respectively.

Persons desiring to board any of the cars C, C' or others which may be in the bank may signify their intention to do so by operating up and down car-calling buttons mounted at the several floors past which the cars move. It will be understood that the elevator car C will stop at the first and sixth floors (the terminal floors) without the

necessity of providing call buttons for these floors. Hence, I have illustrated an up button F₂U and a down button F₂D at the second floor for permitting a prospective passenger to register his desire to travel either upwardly or downwardly from the second floor.

In like manner, buttons F₃U, F₃D, F₄U, F₄D, F₅U and F₅D may be manipulated to signify the intention of persons to travel upwardly or downwardly from the third, fourth and fifth floors, respectively.

A floor relay is provided for each of the buttons to be controlled, thereby to register the call initiated by the button and to maintain the call registered until it has been answered, without making it necessary that the passenger shall hold the button in depressed condition until the car answers the call. Floor-call registering relays R₂D and R₂U are associated, respectively, with buttons F₂D and F₂U, while buttons F₃U, F₃D, F₄U and F₄D, etc. have similar relays R₃U, R₃D, R₄U, R₄D, R₅U and R₅D associated therewith.

Each of the relays R₂U and R₂D, etc. is provided with two energizing coils wound in opposition to each other in such manner that one of the coils, when energized, causes the relay to be actuated to close its contact members while the operation of the other coil opposes the effect of the first coil to cause the relay to open its contact members.

The car-calling circuits, controlled by buttons F₂U, F₂D and relays R₂U and R₂D etc., extend in parallel relation to corresponding groups of segments on the floor selectors, one of which is associated with each car in the bank of elevators to which my invention is to be applied. The floor selector FS associated with car C comprises a suitable base 20 upon which are mounted a plurality of groups of contact segments arranged to be engaged by a plurality of contact brushes carried upon a movable arm MA moved over the face of the floor selector FS by means of a screw 21 connected to be driven in any suitable manner corresponding to the movements of the elevator car past the various floors which it serves.

The movable arm MA is suitably mounted upon the screw 21 to be rocked about the screw to bring all of the contact brushes to the left of the screw 21 into a position of possible engagement with the contact segments on the left-hand side of the floor selector FS when the car is travelling upwardly and to simultaneously move the contact brushes on the right-hand side of the movable arm MA out of possible engagement with the segments on the right-hand side of the floor selector FS when the car is travelling upwardly by reason of a throw-over magnet US which is energized when the car is to travel upwardly. In a similar manner, a throw-over magnet DS may be energized when the car is travelling downwardly to reverse the position of the movable arm MA for permitting, under these circumstances, the engagement of only those contact brushes on the right-hand side of the arm MA to engage their associated selector segments.

The contact segments on floor selector FS are divided into groups 22, 23, 24, 25, 26, 27, 28, 29, 30, 31, 32 and 33, each of which groups comprises a segment for each of the floors served by the car arranged in two parallel lines distinguished from each other by the reference characters X and Y, with the exception of groups 25 and 30, which groups have all of the contact segments arranged in a single vertical line. The segments in group 22 are connected to the up hall lan-

terns, the segments in line X being connected, respectively, to up hall lanterns 2LU, 4LU and 6L for the even numbered floors, while the segments in the other or Y line are connected, respectively to up hall lanterns 3LU and 5LU associated with the odd numbered floors, (the third and fifth floors), respectively.

The segments in group 22 are arranged to be traversed by a pair of contact brushes 22a carried upon the movable arm MA, the brush X in this group being arranged to make contact successively with the segments in the X line of group 22, while the brush Y is arranged to make contact with the segments in the Y line of group 22.

15 The contact segments in group 23 are, in like manner, divided into two lines X and Y, those in line X being connected to resistors 35 and 37, while those in line Y are connected, respectively, to resistors 34 and 36. Brushes 23a, including an X brush and a Y brush, are arranged to traverse lines X and Y, respectively, of the segment group 23.

25 Contact segments in group 24 are, in like manner, divided into two lines X and Y, those segments in the X group being connected, respectively, to be energized in response to floor calls registered by relays R2U and R4U, while those in the Y line are arranged to be energized in response to floor calls registered by relays R3U and 30 R5U, respectively. A group of contact brushes 24a, including an X brush and a Y brush, are arranged to traverse the respective X and Y lines of segment group 24.

35 The segments in group 25 are respectively connected to the cancellation coils R2UC, R3UC, R4UC and R5UC and are arranged to be traversed by a brush 25a carried by the movable arm MA.

Contact segments in group 26 are arranged in two lines X and Y. Those segments in line X 40 are connected to the energizing coil of inductor-energizing relay 7X, while those in line Y are connected to the energizing coil of inductor-energizing relay 7Y. The segments in group 26 are arranged to be traversed by a pair of brushes 26a, one of these brushes X being arranged to traverse the X line and the other, Y, to traverse the Y line of segment group 26.

50 Segment group 27 is also divided into an X line and a Y line, connected, respectively, to the second and fourth floor car buttons C2 and C4 and to the third and fifth floor car buttons C3 and C5 and are arranged to be traversed by a group of contact brushes 27a in like manner comprising an X and a Y brush.

55 In a similar manner, contact segments 28, 29, 30, 31, 32 and 33 are divided into X and Y lines for each group and are arranged to be connected, respectively to the car call buttons, the inductor energizing relays 7X and 7Y, the cancellation coils R2DC, etc. on the floor-call registering relays R2D, etc., the call registering relays R2D, R3D, etc. to transmit the registered calls to the car, to resistors 38, 39, 40 and 41, and to the down floor lanterns 1L, 2LD, 3LD, 4LD and 5LD, in a manner corresponding to the connection of groups 22, 23, 24, 25, 26 and 27 on the left-hand or up-side of the floor selector.

60 Disposed in the center of the floor selector FS, I have illustrated a pair of normally-closed contact switches 42 and 43 to be engaged and opened by a wedge-shaped piece of insulating material 44, as the car respectively arrives at the lowermost and uppermost floors.

65 In order to prevent more than one car in the bank from receiving calls for service at any given

time, I have provided a pair of block relays 4X and 4Y connected to be energized successively as the car C approaches the various floors which it serves. Similarly, block relays 4X' and 4Y' are provided for car C', and for all other cars in the bank. As previously described, I have provided resistors 34, 35, 36, 37 and 38, 39, 40 and 41, or two resistors for each intermediate floor past which the cars operate. The resistors 35 and 37, and 34 and 36 are connected to block relays 4X 10 and 4Y, respectively, through the corresponding segments in group 23 on the left hand or "up" side of the floor selector FS, while resistors 39 and 41 and 38 and 40 are connected to block relays 4X and 4Y through the corresponding segments 15 on the right-hand or "down" side of the floor selector FS.

It will be observed that each resistor is a common member in a circuit having a branch for each car, including a floor selector segment and a block relay for that car. It is, therefore, readily apparent that, if the floor selectors for two or more cars should complete the circuits to the block relays for those cars simultaneously, the voltage drop across the common resistor would 20 be considerably greater than would be the case if only one circuit were completed. Conversely, the voltage drop across the coil of each individual relay would be considerably lessened. Depending upon the ohmic value of the resistor and 25 the characteristics of the coils of the several block relays, the voltage available to the coils under these conditions may be below the "pick-up" or actuating value for the coils. To further decrease the voltage available to each coil, additional resistors (as 105, 105', etc., the operation of which will be hereinafter described) may be arranged for connection in shunt relation to the varicous block relay coils. In this case, upon actuation of any block relay, the voltage drop across 30 the common resistor will be immediately increased, and, upon completion of the circuit to the block relay for another of the cars, will be further increased to such value as to render the voltage available to such other relay below the 35 "pick-up" value for that relay. Under these conditions, the actuated relay will be maintained, for, as is well known, it requires considerably more power to actuate a relay than is required to maintain it actuated. In the preferred embodiment of my invention, I have shown block relays requiring the use of the additional resistors, although, as stated, under certain conditions, such additional resistors may not be required. Either 40 method, properly employed, will permit of the 45 actuation of the block relay for only one car at one time.

In order to cause the elevator car to be stopped in response to the calls for service registered either by actuation of the floor call buttons F2U, 60 F2D, etc., or the car call buttons C2, C3, etc., I have provided a plurality of car-stopping relays, including a pair of floor-call stopping relays 5X and 5Y, respectively, associated with block relays 4X and 4Y and an additional pair of car-stopping relays 6X and 6Y to be controlled from the car buttons C2, C3, etc.

65 Relays 5X and 6X, when actuated, control an inductor-energizing relay 7X to complete a circuit hereinafter described for the coils of inductor relays UR and DR to cause the car to stop level with the floors. A second inductor-energizing relay 7Y is associated with relays 5Y and 6Y for also energizing the coils of the inductor relays UR and DR.

My invention will best be understood with reference to an assumed elevator operation. Assuming that elevator car C is standing at the first floor and it is desired to start this car 5 upwardly, the attendant on the car will move car switch Cs in a clockwise direction to complete a circuit for the up-direction switch 1 to thereby cause the car to start upwardly. The circuit for up-direction switch 1 extends from line conductor L1, through conductor 45, contact members 46 on stop inductor relay SR, conductors 47 and 48, the coil of up-direction switch 1, conductor 49, contact members 50, 51 and 52 on car switch Cs and conductors 53 and 54, to line conductor L2.

Up-direction switch 1, when energized, supplies current in one direction to the separately-excited field winding GF of generator G, which circuit extends from line conductor L1, through conductors 55, 56 and 57, contact members b on up-direction switch 1, conductors 58 and 59, field winding GF, conductors 60 and 61, contact members c on up-direction switch 1, conductor 62, resistor R and conductor 63, to line conductor L2. Generator G will, therefore, supply current to the armature of the elevator motor EM to cause this motor to start the car in the upward direction at a speed determined by the value of the resistor R.

Up-direction switch 1, when energized, also completes a self-holding circuit for itself which extends from line conductor L1, through conductors 45, etc., to conductor 48, as previously described, thence through the coil of up-direction switch 1, conductor 64, contact members a on up-direction switch 1 and conductor 65, to line conductor L2. Hence, until stopping inductor relay SR opens its contact members 46, the car will continue to travel in the upward direction at slow speed.

If it is desired to operate the elevator car C at high speed, the attendant may move car switch Cs to a further position in a clockwise direction to complete a circuit for actuating speed relay 3 which circuit extends from line conductor L1 through conductors 45 and 66, contact members 67 on down slow-down inductor relay DR, conductor 68, contact members 69 on up slow-down inductor relay UR, conductor 70, the coil of speed relay 3, conductor 71, thence, in series relation, through normally closed contact members c on each of the car-stopping relays 6X and 6Y and floor stopping inductor relays 5X and 5Y, thence, by way of conductor 72, contact members 73, 51 and 52 on car switch Cs and conductors 53 and 54, to line conductor L2.

Speed relay 3, when energized, shunts resistor section R out of the generator-field-winding circuit by way of its contact members b, thus supplying full line voltage to the field winding GF of the generator G, and this relay also completes a self-holding circuit for itself which extends, as previously described, from line conductor L1, through conductors 45 and 70, the coil of speed relay 3, conductor 74, contact members a on speed relay 3 and conductor 75, to line conductor L2. Hence, until either down slow-down inductor relay DR or up slow-down inductor relay UR is actuated to open its associated contact members, the car will continue to travel upwardly at high speed.

It will be observed that, at the time at which the car C was standing at the first floor, the wedge-shaped piece of insulating material 44 on movable arm MA of the floor selector FS was in

engagement with, and separated, contact members of normally closed switch 42 on floor selector FS, thereby opening the circuit for down-direction determining relay 8 and permitting the completion of a circuit for up-direction-determining relay 9. The circuit for up-direction-determining relay 9 extends from line conductor L1, through conductors 55 and 77, the normally closed contact members of switch 43 on floor selector FS, conductor 78, the coil of up-direction-determining relay 9, conductor 79, normally closed contact members a on down-direction-determining relay 8 (now closed since this relay is deenergized), conductor 80, normally closed contact members on the reversing button D carried upon the car C and conductors 81, 82 and 84, to line conductor L2.

Up-direction-determining relay 9, when energized, completes a circuit for energizing the up selector throw-over magnet US to cause the left-hand groups of brushes on the movable arm MA of floor selector FS to be moved into possible engagement with the left-hand or up groups of segments 22, 23, 24, 25, 26 and 27 and to move the left-hand groups of brushes out of possible engagement with segment groups 28, 29, 30, etc. The circuit for magnet US extends from line conductor L1, through conductor 83, the coil of up-throw-over magnet US, conductor 84, contact members b on up-direction determining relay 9 and conductor 85, to line conductor L2.

Assuming now that a person at the third floor desired to travel upwardly and actuated button F3U, call registering relay R3U will have been energized by way of a circuit which extends from line conductor L1, through conductor 86, button F3U, conductor 87, the energizing coil 88 on relay R3U and conductors 89, 90 and 54, to line conductor L2. The energization of call-registering relay R3U supplies current from line conductor L1 to segment 91 in Y line of group 24 on the floor selector FS by way of a circuit extending from line conductor L1 through conductor 92, the contact members of relay R3U, conductor 93, conductors 93 and 94 to a junction point 95, whence one branch extends, by way of conductor 96, to segment 91 in group 24, while another branch extends, by way of conductors 97 and 98, to a corresponding contact segment 91' on floor selector FS' associated with the second car C' in the bank and, as may readily be observed, to the corresponding contact segment on as many other floor selectors as there are cars in the bank of elevators to which my invention may be applied.

Thus, the call for service at the third floor is registered and maintained upon the floor selectors for all of the cars in the bank. However, assuming that car C is the first car to approach the third floor, it will be observed that brush Y of group 23a will move into engagement with contact segment 98, constituting one of the segments in the Y line of group 23. A circuit will, therefore, be completed for energizing block relay 4Y which extends from line conductor L1, through resistor 36, conductors 99 and 100, segment 98 on floor selector FS, brush Y of group 23a on floor selector arm MA, conductor 101, the coil of block relay 4Y, conductors 102, 103 and 104, the normally closed contact members of a bypass switch BP and conductors 82 and 54, to line conductor L2.

Upon energization, relay 4Y closes its contact members a to insert the additional resistor 105 in the circuit just traced. As previously described, the effect of resistor 105 is to immediately in-

crease the voltage drop across resistor 37 and to decrease the voltage across the coil of relay 4Y. If, while relay 4Y is actuated, car C' should approach the third floor, travelling in the up di-

rection, a circuit would be completed through its floor selector FS' to its block relay 4Y', similar to the one traced for relay 4Y. However, as previously described, upon completion of such second circuit, the voltage drop across resistor 37 is further increased, and the voltage available to the coil of relay 4Y' is reduced to a value below that necessary to actuate it. Car C' does not, therefore, receive the call and so passes by the floor. As hereinafter described, under such conditions, the call cancellation means associated with the car C' are ineffective to cancel the registered call.

The relay 4Y, when energized, partially completes a circuit for floor-call stopping relay 5Y by way of its contact members b, which is completed by the engagement of the Y brush in group 24a on floor selector arm MA with an energized contact segment in the Y line of segment group 24. Hence, since segment 91 is now energized, as hereinbefore described, a circuit is completed for energizing floor-call stopping relay 5Y which extends from line conductor L1 to segment 91, as previously described and thence, by way of the Y brush in group 24a, conductors 106, 107 and 108, contact members b and block relay 4Y, conductor 109, the coil of floor call stopping relay 5Y, conductor 110, conductors 142 and 104, bypass button BP, and conductors 82 and 54, to line conductor L2.

Car-call stopping relay 5Y, when energized, closes its contact members a to complete a circuit for the hall lantern corresponding to the floor at which the car is next to stop (in this case, the third floor hall lantern 3LU) from line conductor L1, through conductors 83 and 111, hall lantern 3LU, conductor 112, segment 113 in the Y line of segment group 22, the Y brush of group 22a on selector arm MA, conductors 114, 115 and 116, contact members a on relay 5Y, conductors 117, 142 and 104, bypass button BP and conductors 82 and 54, to line conductor L2. Floor lantern 3LU will, therefore, be energized to indicate that car C is to stop at this floor to pick up the prospective passenger. It will be observed, from an inspection of the floor selector FS, that, at the instant of lighting the floor lantern 3LU, the car was less than one-fourth the distance to the second floor. In other words, slightly less than two floors away from the point at which the stop is to be made. This distance is indicated by the fact that segment 113 has its lower extremity at a point less than one-fourth the distance between the broken lines crossing the floor selector FS bearing the legend 1st and 2nd, these broken lines representing the position of the movable arm MA when the car C is exactly level with the corresponding floor. Hence, the prospective passenger has ample opportunity to move to a position in front of elevator car C to be ready to board that car when it arrives level with the floor.

Floor-call stopping relay 5Y, when energized, also partially completes a circuit for energizing inductor-energizing relay 7Y which is completed when the Y brush in group 26a engages the third floor segment in the Y line of group 26. This circuit extends from line conductor L1, through conductors 55 and 56, contact members b on relay 5Y, conductors 119, 120 and 121, the Y brush in group 26a, segment 122 constituting the third floor segment in the Y line of segment group 26,

conductor 123, segment 124, conductor 125, the coil of inductor energizing relay 7Y, throw-over switch 178, conductor 118 and conductor 75, to line conductor L2.

Inductor-energizing relay 7Y, when actuated, prepares a circuit for energizing the inductor relay UR provided the car switch Cs has been returned to the neutral or off position. As will be understood from the description previously given relative to the starting of the elevator car, the car switch may be centered as soon as either of the direction switches 1 and 2 and speed relay 3 are energized, without interrupting the operation of the car, since these switches are maintained in operative condition by way of their self-holding circuits. Hence, at the time inductor-energizing relay 7Y is energized, the car switch Cs should be in the neutral or off position.

The circuit for energizing inductor relay UR extends from line conductor L1, through conductor 45, the coil of inductor relay UR, conductor 129, contact members e on up-direction switch 1, conductors 130 and 131, contact members of inductor-energizing relay 7Y, conductor 132, throw-over switch 133, conductor 134, contact members 135, 51 and 52 on car switch Cs and conductors 53 and 54, to line conductor L2.

As is described in the Bouton application previously mentioned, the car will continue to travel after energization of the coil of the inductor relay until the car, in its approach to the floor at which it is desired to stop, brings the inductor relay UR adjacent an inductor plate mounted in the hatchway at a predetermined distance in advance of the selected floor level. Hence, after the car C, in its upward travel, brings inductor relay UR adjacent to its cooperating inductor plate mounted at that distance in advance of the third floor at which deceleration must start in order that the car may be stopped at the third floor level, relay UR will be energized to open its contact members 69, thereby breaking the self-holding circuit for speed relay 3. Deenergization of speed relay 3 reinserts resistor R in series relation to the generator field winding GF to thereby cause reduction of the car speed from its high speed to a lower speed.

Deenergization of relay 3 also completes a circuit for energizing the coil of inductor relay SR which extends from line conductor L1, through conductors 45 and 126, the coil of inductor relay SR, conductor 127, normally closed contact members c of relay 3, conductors 128 and 166, the contact members of relay 7Y, conductor 132, throw-over switch 133, conductor 134, contact members 135, 51 and 52 of the car switch Cs, and conductors 53 and 54 to line conductor L2.

As the car continues to travel, at reduced speed, towards the third-floor level, inductor relay SR will, in turn, be brought adjacent to an inductor plate cooperating with this relay, which plate is mounted substantially at a level with the third floor. Actuation of inductor relay SR by its inductor plate will cause the opening of contact members 46 on relay SR to thereby open the self-holding circuit for up-direction switch 1, cutting off excitation of the generator field winding GF and causing the setting of the brake (not shown) to stop the car at the third floor level.

In the present assumed operation, the call for service at the third floor was registered prior to the time that the slow-down inductor relay UR passed its associated inductor plate. It will be apparent, however, that, had the call been registered after relay UR passed its associated induct-

tor plate but before relay SR passed its associated inductor plate, the stopping means of car C would have been ineffective to cause that car to respond to the call, by reason of the interlock between the 5 coils of these relays, which provides that the stopping inductor relay SR cannot act to bring the car to a stop until inductor relay UR has acted to slow the car down to landing speed.

It will be observed that, during the entire time 10 the car is decelerating and making the stop at the third floor, brush Y of group 23a on floor selector arm MA remains in engagement with the contact segment 98 associated with the third floor. This is illustrated in the drawing which 15 shows that segment 98 extends upwardly slightly beyond the dotted line indicating the third-floor level. Hence, during the entire time the car is decelerating to make the stop at the third floor and also during the entire time the car is standing at the third floor, the circuit for block relay 4Y is maintained. Hence, during all of this time, 20 the signal which originated from the third floor by actuation of button F3U is rendered ineffective to be transmitted to any of the other cars in the 25 bank.

Also, it will be observed that, during the entire time the car is decelerating to make the stop and is standing at the third floor, brush Y of 30 brush group 22a on floor selector arm MA remains in engagement with the floor-lantern segment 113 to maintain floor lantern 3LU illuminated. Hence, a prospective passenger desiring to travel upwardly and arriving in sight of the elevator during the time car C is making the 35 stop, will be immediately notified as to the direction in which the car is to travel when it leaves the third floor. This person may board car C if it is travelling in the direction in which he desires to go without making it necessary that 40 he should operate the third-floor button F3U, and also making it unnecessary that another car in the bank should make the stop at the third floor.

This is perhaps more clearly illustrated by the 45 statement that it has been observed that persons arriving in front of the elevator bank, in the habit of pressing the call buttons for the floors, will operate the button, even though a car is standing at that floor. It will be observed that, 50 in my system, even though this unnecessary operation of the button is made, the registration of the call will not cause another car in the bank to stop at that floor because, during all of the time within which the car is decelerating to stop 55 and is standing at a floor, the call-registering system is disabled to prevent the receipt of a registered call by any of the cars.

Since the hall call for the floor at which a car 60 is standing or for which a car is decelerating to make a stop is maintained independent of the call-registering buttons and relays for that floor and, since the block relay 4Y (or 4X) for that floor prevents the effective registration of a call for that floor for any other car, it is immaterial 65 at what time, between the initial picking up of the call and the departure of the car from the floor, the cancellation of the call is effected. However, in view of the possibility that, while the car is standing at a floor, a prospective passenger may inadvertently operate the call button 70 for that floor to register a call, which, if not cancelled, will cause the unnecessary stopping of another car in the bank, I have arranged my system to cancel the registered calls when the car leaves the floor after the stop has been made.

As has previously been explained, each of the call-registering relays R2U, R3U, etc. have arranged thereon a cancellation coil wound in opposition to the pick-up coil for that relay, which cancellation coil, when energized, neutralizes the effect of the pick-up coil to permit the relay to drop out and open its contact members. As has also been previously explained, the cancellation coils for each of these relays are respectively connected to corresponding segments on the floor 10 selector FS arranged in group 25. From an inspection of the drawing, it will be observed that the segments in group 25 are relatively short and are so located as to be engaged by brush 25a only when the car is approximately level with the 15 corresponding floor.

Hence, when the car C is standing at the third floor level, brush 25a will be in engagement with contact segment 136 of segment group 25. However, it will be observed that the circuit which 20 supplies current to brush 25a extends through a counter E. M. F. relay CEMF. This relay has its coil so connected across the conductors connecting the armature of the generator G with the armature of the elevator hoisting motor as 25 to be energized by the voltage supplied to the elevator motor. The coil of this relay is to be so selected that it will pick up when the car speed is above a relatively low value but will not drop out its contact members until the car speed is 30 reduced to approximately zero. Also, it will be observed that the circuit for brush 25a extends through contact members d on either the up-direction switch 1 or down-direction switch 2.

Hence, the only time at which current will 35 be supplied to brush 25 is when the direction switch has been actuated to start the car after a stop has been made and before the speed of the car has reached such value as will cause actuation of relay CEMF. In other words, the 40 only time brush 25 will receive current is when the car is restarting after making a stop. The circuit through brush 25 for energizing the cancellation coil R3UC for the third floor relay R3U 45 extends from line conductor L1, through conductor 92, the contact members of relay R3U, conductor 93, cancellation coil R3UC, conductor 137, the junction point 138, whence one branch extends by way of conductor 139, contact segment 136 of group 25, brush 25a, conductor 140, normally closed contact members of counter 50 E. M. F. relay CEMF, conductor 141, contact members d on up-direction switch 1, conductors 142 and 104, normally closed contact members of by-pass switch BP and conductors 82 and 54, to line conductor L2. Hence, upon restarting the 55 elevator car C after making the stop at the third floor, call-registering relay R3U will be restored to its non-operating position.

The car may proceed upwardly, stopping at all 60 of the floors for which calls for service have been registered by actuation of the corresponding floor buttons, the operations for each of stops being identical with that described for the third floor.

It will be understood that the actuation of a 65 call button at one of the even-numbered floors, for example, the fourth floor, will cause operation of the floor-call stopping relay 5X or the inductor-energizing relay 1X to stop the car at the corresponding floor and will also operate the floor lantern for the corresponding floor. For the even numbered floors, block relay 4X, instead of relay 70 4Y, will be effected to block all of the other cars from receiving the registered call.

Assuming that the passenger who boarded the 75

car at the third floor desires to leave the car at the fourth floor and so notifies the attendant, the attendant will operate push button C4 in the car to register the expressed intention of the 5 passenger.

The actuation of button C4 supplies current to segment 143, constituting one of the X group of segments in group 27, by way of a partial circuit which extends from line conductor L1, through 10 conductors 45 and 144, button C4, conductor 145, to segment 143.

The X segments in group 27 are arranged to be traversed by an X brush of group 27a on floor selector arm MA. From an inspection of the 15 drawings, it will be observed that, while the car is standing at the third floor, the X brush of group 27a is in engagement with segment 143. Hence, actuation of button C4 will immediately complete a circuit for energizing car-call stopping relay 6X which extends from segment 143, through brush X in group 27a, conductor 146, the coil of relay 6X and conductors 182 and 75, to line conductor L2. It will be further observed that, while the car is standing at the third floor, brush X in group 23a is in engagement with segment 147 in the X line of segment group 23 on floor selector FS, so that block relay 4X is energized to prevent any other car in the bank from receiving registered calls for the fourth floor.

30 The energization of car-call stopping relay 6X accomplishes three purposes; first, that of energizing the inductor energizing relay 1X; second, that of causing lighting of the floor lantern at the floor at which the car is to stop and, third, that of preventing the car from accelerating to high speed if the car is within one floor distance of the floor at which it is desired to stop.

The first of these purposes is accomplished by arranging the contact members b on relay 6X to energize brush X in group 26a in the same manner as was described with reference to the operation of relay 5Y. This circuit extends from line conductor L1, through conductors 55, 56 and 148, contact members b on relay 6X, conductors 149, 150 and 151, brush X in group 26a, contact segment 152 in the X line of segment group 26, conductor 153, the coil of inductor energizing relay 1X throw-over switch 177, and conductors 182 and 75, to line conductor L2.

55 In explanation of the reason for causing immediate energization of relays 6X and 1X when the car is standing at the third floor and it is desired to stop at the fourth floor, it should be observed that, with an elevator operating at such speeds as are ordinarily used at the present time, ranging from 600 to 900 feet per minute, the distance required to decelerate a car from high speed may exceed the distance between two adjacent floors. Hence, if a car is standing at one floor 60 and it is desired to stop at the next floor, the car must not be permitted to accelerate to its high speed. Again, when the car is to operate at such high speed, the inductor plate for operating the high-speed inductor relay UR may be located 65 more than one floor distance in advance of the floor which it serves, in order to initiate deceleration from the high speed when the car is at the beginning of the deceleration distance for that floor. Therefore, when the car is standing at the third floor, relay UR will have passed the inductor plate associated therewith for initiating slow down for the fourth floor and, for this additional reason, the car must not be permitted to accelerate to high speed in making the one floor 70 run. Moreover, the inductor-relay coils should

be immediately energized because the car is to approach the slow-down point from even the lower speeds within such a short time after the starting of the car that these relays must be prepared, immediately upon starting the car, to be actuated when they pass the inductor plates associated with them.

The foregoing explanation illustrates why it is necessary that the second function of relay 6X is incorporated in this system. Contact members c on relay 6X are included in the energizing circuit for speed relay 3, so that, even though the attendant should move the car switch Cs to its extreme position, making contact with contact member 13 on car switch Cs, speed relay 3 would not be picked up. The energizing circuit for speed relay 3 was traced herein in describing the starting of the car from the first floor and, therefore, will not be repeated at this point.

The third function ascribed to relay 6X, namely, that of lighting the floor lantern, is accomplished by contact members a on this relay, which, when actuated, complete a circuit to brush X in group 22a on selector arm MA to supply current through the fourth-floor hall-lantern segment 154 to thereby light lantern 4LU to indicate that a car is to stop at the fourth floor. This signal is given for the benefit of any persons who, arriving in front of the elevator bank after the car is within a predetermined distance from the fourth floor, with a call on the car register to make it necessary that this car shall stop at the fourth floor, will be notified that the particular car is already under the necessity of stopping at that floor and that the prospective passenger is not, therefore, required to operate the call button F4U at that floor.

The car, upon being started from the third floor, will accelerate only to a slow speed and 40 subject to the operation of stopping relay SR, will be automatically stopped level with the fourth floor, in a manner similar to that described for the third-floor stop.

50 Button C4, when depressed, will remain in such depressed condition by the effect of a hold-down magnet 155 which is arranged to be constantly energized except for a momentary period at the ends of travel of the car. The energizing circuit for coil 155 is controlled by direction-determining relays 8 and 9 in such manner that, when the car arrives at the upper terminal and the direction-determining relay 9 is deenergized to cause the changing over of the position of floor selector arm MA from the up side of the floor selector FS to the down side thereof, the period between deenergization of direction-determining and the energization of direction-determining relay 8 will cause a momentary deenergization of coil 155 to release all of 60 the car buttons C2, etc. which may have been actuated during the upward trip of the car. It will be observed that the circuit for coil 155 extends from line conductor L1, through conductors 45 and 156, the coil 155, conductor 157, contact members c on up direction-determining relay 9 and conductor 85, to line conductor L2, or, when the car is travelling downwardly, the circuit extends, through conductor 157, contact members c on down-direction determining relay 70 8 and conductor 35, to line conductor L2.

75 It will be observed from the foregoing description that, as the car C moves upwardly, it will connect block relay 4X and its associated resistor to the circuits extending in parallel re-

lation to all of the floor selectors for all of the cars in the bank to disable the remainder of the cars from receiving calls for service from any floor within a zone of operation in advance of car 5 C which is defined by the extent of the segments in group 23 in advance of the corresponding position of the car. In other words, as car C moves upwardly in the shaft, it provides a moving block in advance of its position, within which all call 10 signals are disabled to actuate the stopping devices for the remaining cars in the bank.

It will be further observed that the blocking of the calls from the remainder of the cars is effective whether the car is moving or standing 15 at a floor.

While the foregoing description of my system 20 has dealt with the automatic stopping of the car in response to the registered calls, my system is equally applicable, as a signalling device, for signalling an attendant-controlled elevator that a stop is to be made, whereupon the attendant manipulates the control of the elevator car in such manner as will cause the car to respond to the registered call.

25 For this reason, I have illustrated a pair of flash signal lamps 158 and 159 as carried by the car C for signaling to the attendant that a stop is to be made. The signal lamps 158 and 159 are so connected in circuit with a switch 30 160 that the operation of these lights may be cut out if the car is to operate as one in which the car is automatically stopped by the push buttons rather than by the attendant.

35 The signal lamps 158 and 159 are arranged to be energized as the car approaches the signal zone in advance of the floor for which a call has been registered by connecting these lamps in a circuit which will be completed when the brushes in group 24a make contact with the corresponding 40 floor segments in segment group 24 on floor selector FS.

45 It will be observed that a relay 161 is provided having three energizing coils 162, 163 and 164, any of which is capable of actuating the relay. It will be further observed that coil 164 is connected through contact members c on block 50 relays 4X and 4Y to be energized when the X brush or the Y brush of group 24a contacts with energizing segments in the X line or the Y line of segment groups 24. Hence, assuming that a person at the third floor desires to travel upwardly and operates button F3U, current will be supplied to contact segment 91 through conductors 92 to 96, in the manner previously described for the automatic operation. Therefore, as the car C approaches the third floor, and contact brush Y of group 24a engages segment 91, relay 161 will be actuated by way of a circuit which extends from segment 91, through brush Y in group 24a, conductors 106, 107, and 165, contact members c on block relay 4Y, conductor 167, coil 164 of relay 161 and conductor 168, manually operated switch 169 and conductor 85, to line conductor L2.

60 Relay 161, when actuated, completes a circuit for energizing either lamp 158 or lamp 159, dependent upon whether the car is moving or is standing at a floor at the time brush X of group 24a engages contact member 91.

65 Two lamps are provided for achieving the result of distinguishing between calls for one floor runs and calls for runs of greater distance than one floor, in order that the attendant may be pre-warned before starting the car whether the car is to operate at a high speed or at a lower speed 70 in order to make the next stop. If the car is

standing at a floor, only signal lamp 159 is capable of operation since the circuit for this lamp extends in series relation through normally closed contact members g on both of the direction switches 1 and 2, whereas the circuit for the other lamp 158 extends through normally open contact members on either the up-direction switch 1 or the down-direction switch 2. Hence, when the car is stationary, the circuit for lamp 158 is broken, while, when the car is moving, the circuit for lamp 159 is broken.

75 Since, in our assumed example, the car was moving, a circuit will be completed for signal 158 which extends from line conductor L1, through conductors 55, 56 and 170, contact members of signal relay 161, conductor 171, contact members f on up-direction switch 1, conductor 172, signal lamp 158, conductor 173, throw-over switch 168, and conductors 81, 82 and 54, to line conductor L2. The energization of lamp 158 will warn the 20 operator that he must make a stop at the third floor and he, therefore, returns the car switch Cs to neutral position.

80 When my system is to be utilized in signaling, rather than an automatic stopping system, throw-over switch 133 should be moved from the full-line position illustrated to a position indicated by broken lines. Such changing of the throw-over switch 133 places the inductor-relay coils directly under the control of the car switch Cs, independently of inductor-energizing relays 1X or 1Y. Hence, when the operator acting in response to the signal, centers the car switch, a circuit for energizing the coil of inductor relay UR is completed from line conductor L1, through conductors 45, coil of relay UR, conductor 129, contact members e on up-direction switch 1, conductors 130, 131 and 166, throw-over switch 133, conductor 134, contact members 135, 51 and 52 on car switch Cs and conductors 53 and 54, to line conductor L2. Hence, as the car in its movement towards the third floor, brings inductor relay UR past its associated inductor plate, the car will be slowed down, and a circuit completed for the coil of inductor relay SR, extending from line conductor L1, through conductors 45 and 126, coil of relay SR, conductor 127, contact members c on relay 3, now deenergized, conductor 128, conductor 166, and thence to line 2 as described for relay UR. When relay SR passes its associated inductor plate, it will act to stop the car as previously described.

85 Assuming that the passenger boarding the car at the third floor desires to travel to the fourth floor and that the attendant operates button C4 in the car, as previously described, it will be observed that signal lamp 159 will be energized to indicate that a stop is to be made at the next floor.

90 It will be observed that, when the car is standing at the third floor, block relay 4X will be energized by virtue of the X brush in group 23a being in contact with the contact segment 147 in the segment group 23.

95 Actuation of button C4 will supply current to segment 143 in group 27, as was previously described with reference to the full automatic operation and, since the car is standing at the third floor, brush X of brush group 27a will be in contact with segment 143, and a circuit for energizing coil 162 of signal relay 161 will be completed which extends from line conductor L1, through the button C4 and segment 143, as previously described, brush X in group 27a, conductors 146 and 174, the coil 162 of signal relay 161 and con-

ductor 168, manual switch 169 and conductor 85, to line conductor L2.

Energization of relay 161 will complete a circuit for energizing both of signals 158 and 159, only one of which, however, will be actuated; in this case, signal 159, since the car is standing at the third floor. The circuit for signal 159 extends from line conductor L1 to contact members of signal relay 161, as previously described, and thence, 10 by way of conductor 171, contact members g on up-direction switch 1 (now closed because the car is stationary), conductor 175, contact members g of down-direction switch 2 (now closed since the car is stationary) and conductor 176, signal lamp 159, throw-over switch 160, and conductors 81, 82 and 54, to line conductor L2.

It will, therefore, be observed that my blocking system may be utilized with a manually controlled elevator in which the attendant operates the car 20 in response to signals as well as to an elevator car in which the stopping of the car is automatically accomplished in response to the operation of call-registering push buttons.

Suitable manually operated switches 177 and 25 178 may be placed in the circuits for relays 1X and 1Y to cut out the operation of these relays when the car is to be operated as a manually-controlled elevator, since these relays will perform no necessary function when the car is operating under direct manual control.

It will be further observed that, whether the car is operating as a full automatically controlled car or as a manually controlled car, the effect of blocking relays 4X and 4Y is to prevent the reception, by any car, of a call for service within the zone controlled by these relays when one of the cars in the bank has previously entered the zone and remains therein. In this manner, 35 all the cars will be caused to stop only at the floors for which service is actually desired, and a following car overtaking the first car will receive no signals to stop until after it has passed beyond the zone which, at that time, is under the control of the first car.

On the other hand, it will also be observed that the circuits for block relays 4X and 4Y, as well as the circuits for relays 5X, 5Y, extend through the bypass switch BP. Hence, if for any reason the attendant on the car is unable to answer the calls for service at the various floors and operates the bypass button BP, the block relays will not function to prevent other cars from receiving the calls which must be bypassed. The floor lanterns, indicating that the car is to stop, will not be lighted nor will the inductor-energizing relays 1X or 1Y be energized to cause the stopping of the car if the car is under automatic control, or signal lamps 158 and 159 will not be energized in the event that the car is under manual control with signals. In this way, unless and until a call has been actually answered by the stopping of a car at the corresponding floor in response thereto, the registered call is maintained.

For example, if the car C, upon arriving at the third floor, already contains so many passengers that it was impossible to receive all of the persons at the third floor desiring to board the car, the attendant could operate the bypass button, thereby permitting the same registered call to be transferred to the next car which approached the floor thereafter without making it necessary that car C shall have moved out of the block zone set up by the original actuation of block relay 4Y.

However, the circuits for the coils of relays 6X, 75 6Y, and 1X and 1Y do not go through the bypass means and

button BP. Since relays 6X and 6Y are energized by way of circuits extending through the car buttons, it becomes apparent that, whereas the operator can bypass calls for service registered at the floor landings, he cannot bypass a floor at which a passenger wishes to leave the car.

Hence, it will be observed that I have provided a system in which a registered call may be received by only one car in the bank serving the floors from which such calls originated, and that such registered calls will be maintained actuated until the car has stopped at the floor and has restarted after making the stop, thereby avoiding the necessity of requiring the passengers to again operate the call-registering buttons in the event that, for some reason, the first car to take control of the registered calls could not accommodate all or any of the passengers desiring service.

While the described and illustrated form of my invention is the preferred embodiment, it is to be understood that the description and illustration is illustrative of the principles of my invention, and I do not desire to be limited to any of the details shown therein except as defined in the appended claims.

I claim as my invention:

1. In an elevator signaling system for a plurality of cars operable past a floor, call-receiving means and circuits therefor individual to each car for receiving calls for service at said floor, 30 electromagnetically operable means for each car, operable upon the application of voltage above a predetermined value, to render the call-receiving means for that car effective to receive calls for service, a circuit for said floor having a portion 35 thereof common to all of said cars, and a plurality of branches thereof, one for each of said cars, each branch including the said electromagnetic operating means for that car, means individual to each car and operable correspondingly 40 to the position of that car for completing the branch of said circuit for that car when said car is within a predetermined distance of said floor, and means in said common portion of said circuit operable upon the completion thereof 45 through any branch for rendering the voltage available to the remainder of the said branches below the said predetermined value.

2. In an elevator signaling system for a plurality of cars operable past a floor, call-receiving means and circuits therefor individual to each car for receiving calls for service at said floor, electromagnetically operable means for each car and operable, upon application of voltage above a predetermined value, to render the call-receiving means for that car effective to receive calls for service at said floor, a circuit for said floor having a portion thereof common to all of said cars, and a plurality of branches thereof, one for each of said cars, each branch including the electromagnetic operating means for that car, means individual to each car and operable correspondingly to the position of said car with respect to said floor for completing the branch of said circuit for said car when said car is within a predetermined distance in advance of said floor, and means, including resistance means in said common portion of said circuit, operable upon completion thereof through any branch for rendering the voltage available to the remainder of the said branches below the said predetermined value.

3. In an elevator signaling system for a plurality of cars operable past a floor, call-receiving means and circuits therefor individual to each

car for receiving calls for service at said floor, electromagnetically operable means for each car operable upon application of a voltage above predetermined value to render the call-receiving means for that car effective to receive calls for service, a circuit for said floor having a portion common to all of said cars and including voltage-modifying means, and a plurality of branches, one for each of said cars, each branch including the electromagnetic operating means for that car, means individual to each car and operable correspondingly to the position of said car with respect to said floor for completing the branch of said circuit for that car when said car is within a predetermined distance in advance of said floor, and additional means in each branch circuit operably responsive to the actuation of the electromagnetic operating means in that branch for rendering the voltage available to the remainder 10 of said branches below the said predetermined value.

4. In an elevator signaling system for a plurality of cars operable past a floor, call-receiving means and circuits therefor individual to each car for receiving calls for service at that floor; electromagnetically operable means for each car operable upon application of a voltage above a predetermined value to render the call-receiving means for that car effective to receive calls for service; a circuit for said floor having a portion thereof common to all of said cars and including a voltage-modifying means, and a plurality of branches, one for each of said cars, each branch including, for connection in parallel relation, resistance means and the said electromagnetic operating means for that car, means individual to each car and operable in correspondence with the position of said car with respect to said floor for completing the branch of said circuit for that car when the said car approaches within a predetermined distance in advance of the said floor, and means, operably responsive to the actuation of the said electromagnetic operating means for that car, for connecting said electromagnetic operating means and said resistance means in parallel relation, thereby rendering the voltage available to the remainder of the said branches below the said predetermined value.

5. In a signaling system for a bank of elevators, a plurality of elevator cars operable past a floor, call-registering means on said floor common to all of the said cars, call-receiving means for each car, a circuit including said call-receiving means for each car and said call-registering means, electromagnetic means for each of said cars operable only upon the application of a voltage above a predetermined value, circuits therefor, means individual to each car and operable correspondingly to the position thereof relative to said floor for completing the circuit to the electromagnetic means for that car, means operated by each of said electromagnetic means operable to close the call-receiving circuit for the corresponding car when the said call-registering means has been operated, a portion of each of said circuits for the said electromagnetic means being common to the others, and a voltage-modifying means therein, a constant voltage being available in said circuit for the said electromagnetic means, means associated with each of the said electromagnetic means whereby the voltage drop across the said voltage-modifying means is increased when one of said electromagnetic means is actuated and the voltage to be supplied across

the others of said electromagnetic means is decreased below the said predetermined value.

6. In an elevator signaling system for a plurality of elevator cars operable past a floor, call-receiving means and circuits therefor individual to each car for receiving calls for service at said floor, electromagnetically operable means for each car operable upon application of voltage above a predetermined value to render the call-receiving means for that car effective to receive calls for service, a circuit for said floor having a portion thereof common to all of said cars, and a plurality of branches, one for each of said cars, each branch including the electromagnetic operating means for that car, means individual to each car and operable correspondingly to the position of said car with respect to said floor for completing the branch of said circuit for said car when said car is within a predetermined distance in advance of said floor, means in said common portion of said circuit operable upon the completion thereof through any branch for rendering the voltage available to the remainder of the said branches below the said predetermined value, and means in each of said branch circuits under the control of an attendant on the corresponding car for rendering the electromagnetic means in that circuit ineffective for operation.

7. In a signaling system for a bank of elevator cars operable past a floor, call means at said floor, means common to all of said cars operable responsive to actuation of said call means for registering and maintaining calls for service at said floor, call-receiving means and a circuit therefor for each of said cars, means individual to each car and operable correspondingly to the position of that car relative to said floor for connecting the call-receiving circuit for that car to said call-registering means, electromagnetic means for each of said cars operable only upon application of voltage above a predetermined value, circuits therefor, means individual to each car and operable correspondingly to the position thereof relative to said floor for completing the circuit for the electromagnetic means for that car, switch means interposed in said call-receiving circuit for each car and operable upon actuation of the corresponding electromagnetic means for closing said call-receiving circuit, a portion of each of said circuits for the said electromagnetic means being common to the others and to a voltage-modifying means therein, a substantially constant voltage in the said circuit for the said electromagnetic means, means associated with each of the said electromagnetic means whereby the voltage drop across the said voltage-modifying means is increased when one of the said electromagnetic means is actuated, and the voltage capable of being supplied across the other of said electromagnetic means is decreased below the said predetermined value, means operable correspondingly to the position of said car relative to said floor for restoring said call-registering means to non-operated condition, means in each of said branch circuits under the control of an attendant on the corresponding car for rendering the electromagnetic means in that circuit ineffective for operation and means for preventing actuation of said restoring means.

8. In a signaling system for a bank of elevators, a plurality of elevator cars operable past a floor, call-receiving means for each of said elevator cars and circuits therefor, a portion of each of said circuits being common to the others, call-registering means on said floors in said

- common portion of said circuits for all the call-receiving means, electromagnetic means for each of said cars operable only upon application of a voltage above a predetermined value, a portion of said circuits for the said electromagnetic means being common to the others and a voltage-modifying means therein, a constant voltage being impressed on said circuit including said voltage-modifying means and said electromagnetic means for each of said cars, means individual to each car and operable correspondingly to the movement thereof relative to said floor for completing the circuit including said voltage-modifying means and said corresponding electromagnetic means within a predetermined zone in advance of the floor, means associated with said electromagnetic means operable only when said electromagnetic means is actuated, whereby the voltage across said voltage-modifying means is increased and the voltage across the others of said electromagnetic means is decreased below the normally operable voltage, thus preventing the others of the said electromagnetic means from being actuated after one of the said electromagnetic means has been actuated while the car corresponding to the said actuated electromagnetic means is within the said zone which is in advance of the floor corresponding to the actuated electromagnetic means, the voltage in the circuit including the said voltage-modifying means and the said corresponding electromagnetic means being maintained substantially constant, and means operated by the said electromagnetic means to close the circuit including the said call-registering means and said call-receiving means for the corresponding car when the said call-registering means has been operated.
9. In an elevator signaling system for a plurality of cars operable past a floor, call-receiving means and circuits therefor individual to each car for receiving calls for service at said floor, a blocking zone comprising a call zone extending from one predetermined distance in advance of the said floor to another lesser predetermined distance in advance of the said floor, within which the said call-receiving means may be rendered effective to receive calls for service at said floor, and a stopping zone extending from the said lesser predetermined distance in advance of the said floor to said floor within which the car may be decelerated from high speed to zero speed, electromagnetically operable means for each car operable upon application of voltage above a predetermined value to render the call-receiving means for that car effective to receive calls for service, a circuit for said floor having a portion common to all of said cars, and a plurality of branches thereof, one for each of said cars, each branch including the electromagnetic operating means for that car, means including means defining said blocking zone individual to each car and operable correspondingly to the position of said car with respect to the said floor for completing the branch of said circuit for said car while said car is within said blocking zone, and means in said common portion of said circuit operable upon completion thereof through any branch for rendering the voltage available to the remainder of said branches below the said predetermined value.
10. In an elevator signaling system for a plurality of cars operable past a floor, call-receiving means and circuits therefor individual to each car for receiving calls for service at the
- said floor, a call zone extending from one predetermined distance in advance of the said floor to a lesser predetermined distance in advance of the said floor within which the said call-receiving means may be rendered effective to receive calls for service at that floor, electromagnetically operable means for each car operable upon application of voltage above a predetermined value to render the call-receiving means for that car effective to receive calls for service, a circuit for said floor having a portion common to all of said cars, and a plurality of branches, one for each of said cars, each branch including the said electromagnetic operating means for that car, means including means defining said call zone individual to each car and operable correspondingly to the position of said car with respect to said floor for completing the branch of said circuit for said car while said car is within said call zone, and means in said common portion of said circuit operable upon completion thereof through any branch for rendering the voltage available to the remainder of the said branches below the said predetermined value.
11. In an elevator signaling system for a plurality of cars operable past a floor, car-starting means individual to each car, car stopping means individual to each car, call-registering means at said floor common to all of said cars for registering calls for service at said floor, electromagnetically operable means individual to each car and operable upon application of voltage above a predetermined value to render the said car-stopping means for that car effective for actuation by the said call-registering means for that floor, a circuit for said floor, having a portion common to all of said cars, and a plurality of branches, one for each of said cars, each branch including the electromagnetic operating means for that car, means individual to each car and operable correspondingly to the position of said car with respect to the said floor for completing the branch of said circuit for that car when said car is within a predetermined distance in advance of the said floor, and means in said common portion of said circuit operable upon completion thereof through any branch for rendering the voltage available to the remainder of said branches below the said predetermined value.
12. In an elevator signaling system for a plurality of cars operable past a floor, attendant-controlled means for each car for starting and stopping said car, call-registering means at said floor common to all of said cars, for registering calls for service at that floor, call-receiving means and circuits therefor individual to each of said cars for notifying the attendant to operate said attendant-controlled means to stop said car, electromagnetically operable means individual to each car and operable upon application of voltage above a predetermined value to render the call-receiving means for that car effective for actuation by said call-registering means, a circuit for said floor having a portion common to all of said cars, and a plurality of branches, one for each of said cars, each branch including the electromagnetic operating means for that car, means individual to each car and operable correspondingly to the position of said car with respect to said floor for completing the branch of said circuit for that car when said car is within a predetermined distance in advance of said floor, and means in said common portion of said circuit operable upon completion thereof through any branch for rendering the voltage available to the remainder of said branches below the said predetermined value.

branch for rendering the voltage available to the remainder of said branches below the said predetermined value.

13. In a control system for a plurality of elevator cars operable past a floor, motive means for each of said cars, and a controller for said cars, said controller including switching mechanism individual to each car for controlling the motive means for that car, call means associated with said floor and common to all of said cars for establishing a call for service at that floor, means individual to each car and adapted to respond to the operation of said call means to cause operation of the switching mechanism for that car to stop that car and selective means rendered effective when any car approaches said floor for preventing operation of the switching mechanism for all but one of said cars in response to the operation of said call means, said selective means comprising a circuit including a selective relay actuatable by voltage of a predetermined value and individual to each of said cars, a source of voltage for said circuit, and means responsive to the operation of any of said selective relays for decreasing the voltage available to the others of said relays below said predetermined value, and circuit connections whereby the operation of the stopping switch mechanism for any car depends upon the previous operation of the selective relay for that car.

14. A control system for an elevator car comprising contactors controllable manually, oppositely wound windings operatively associated with said contactors, one effective when energized to actuate said contactors and to maintain them in actuated position and the other to neutralize the action of the maintaining winding to return said contactors to normal position and a circuit controllable by the car and completed to energize said other winding only if the car stops at said landing.

15. A control system for a plurality of elevator cars operable past a floor comprising a control for said floor common to all of said cars; decelerating mechanism for each of said cars operable in accordance with the movements of the associated car to initiate the deceleration of such car; and means for causing the deceleration of one of said cars in response to an operation of said control upon the approach of said one car to said floor and for preventing deceleration of the others of said cars in response to said operation of said control, said last named means comprising means responsive to said operation of said control, preventing mechanism operable when said car reaches a point a predetermined distance in advance of said floor and means operable when said car reaches a second point a lesser predetermined distance in advance of said floor for rendering said decelerating mechanism effective.

16. A control system for a plurality of elevator cars operable past a plurality of floors comprising a control for each of said floors common to all of said cars; decelerating mechanism for each of said cars operable in accordance with the movements of the associated car to initiate the slowdown of the associated car when such car reaches the slowdown point for any of said floors; and control means, for causing operation of the de-

celerating mechanism of one of said cars upon its approach to one of said floors in response to the control for said one floor and for preventing deceleration of the others of said cars in response to said operation of said control, said control means comprising means responsive to said one control, preventing mechanism operable when said one car reaches a point a predetermined distance in advance of the floor corresponding to said operated control, and means for rendering effective said decelerating mechanism for said one car when said one car reaches a point a lesser predetermined distance in advance of the floor corresponding to said operated control.

17. A control system for a plurality of elevator cars operable past a plurality of floors comprising a control for each of said floors common to all of said cars; decelerating mechanism for each of said cars operable in accordance with the movements of the associated car to initiate the slowdown of the associated car when such car reaches the slowdown point for any of said floors; and control means, for causing operation of the decelerating mechanism of one of said cars in response to an operation of one of said floor controls and for preventing deceleration of the others of said cars in response to said operation of said one control, said control means comprising means responsive to said one control, floor selector mechanism operable when said one car reaches a point a predetermined distance in advance of the floor corresponding to said one control to prevent the deceleration of said others of said cars in response to said operation of said one control, and additional floor selector mechanism for rendering effective the decelerating mechanism of said one car and operable when said one car reaches a point a lesser predetermined distance in advance of the floor corresponding to said one control.

18. A control system for a plurality of elevator cars operable past a plurality of floors comprising a control for each of said floors common to all of said cars; a signal for each of said floors individual to each of said cars; decelerating mechanism for each of said cars operable in accordance with the movements of the associated car to initiate the slowdown of the associated car when such car reaches the slowdown point for any of said floors; and control means, for causing the deceleration of one of said cars in response to operation of one of said controls, for preventing deceleration of the others of said cars in response to said operation of said control and for actuating the signal for such one car for the floor corresponding to said operated control, said control means comprising means responsive to operation of said one control, preventing means and signal actuating means operable when said one of said cars reaches a point a predetermined distance in advance of the floor corresponding to said operated control, and means for rendering effective said decelerating mechanism for said one of said cars when that car reaches a point a lesser predetermined distance in advance of the floor corresponding to said operated control.

FRANK E. LEWIS.
